SPINNING SPINDLE

Thor H. Ljunggren, Charlestown, N. H., assignor,
by mesne assignments, to American Viscose
Corporation, Wilmington, Del., a corporation of
Delaware

Application January 19, 1946, Serial No. 642,322

3 Claims. (CL 57—100)

1

This invention relates to spindles for spinning machines, and has for an object to provide a spindle capable of operating at unusually high speed.

Still another object is to provide improved centering devices for holding the blade in desired position at speeds lower than the critical speed and which will permit the blade to find its own rotational center at operating speed above the critical speed.

A further object is to provide improved mounting for the spool on the blade by which the height of the spool may be adjusted as desired.

Further objects and advantages will appear from a description of the invention in connection with the accompanying drawings in which

Figure 1 is a fragmentary top plan view of a spinning frame showing two spindles constructed in accordance with this invention.

Figure 2 is a sectional view to a larger scale on line 2—2 of Figure 1.

Figures 3 and 4 are detail sectional views on lines 3—3 and 4—4, respectively, of Figure 2.

Figure 5 is a detail sectional view similar to a portion of Figure 2 and showing a flexible coupling of a modified form.

Referring to the drawings, 1 indicates a portion of a spinning frame, which as shown best in Figure 2, may be formed as an angle member. It may carry a plurality of spindle mechanisms spaced apart along its length, such mechanisms being indicated generally at 2. Each may be supported from the frame independently of the others by a three-point cushioning support. For this purpose a casing 3 forming a part of each spindle mechanism is provided with three angularly spaced outwardly extending ears 4. Through each of these ears extends a bolt 5 which secures the ear to a resilient mounting comprising a block 6 of cushioning material such as rubber which lies within an opening 7 through the frame support 1, and is provided with a marginal washer 8 which rests upon and is secured to the upper face of the support 1. The bolt 5, as shown in Figure 2, passes downwardly through a central sleeve 10 extending through the block 6, there being positioned washers 11 and 12 above and below the block at the ends of the sleeve 10.

Each casing 3 forms support for a motor stator 15, and preferably this stator is that for a high frequency induction motor, since such motors are capable of very high speeds by subjecting their windings to high frequency alternating currents, the higher the frequency, the higher the speed. Cooperating with the stator is a rotor 16

2

carried by a tubular arbor 17 which is arranged in substantially upright position and is shown as journaled in upper and lower ball bearings 18 and 19, which are shown as of the angular contact type adapted to take end thrust as well as radial load. The outer raceway 20 of the lower bearing 19 rests upon a ring 30 supported by a pair of Belleville springs 31, which in turn, are supported on a ring 32 secured to the bottom face of the casing 3. These Belleville springs 31 act on the bearings 18 and 19 in a way to eliminate radial as well as axial looseness, at the same time give yieldable support in axial direction to compensate for differential linear heat expansion 15 between the arbor and its supporting members.

Extending through the arbor 17 loosely is a blade 35. At the upper end of the arbor 17, this blade 35 is connected to the arbor to be rotated thereby, as by a flexible coupling at 37. As shown

20 in Figure 2, this coupling may comprise a horizontally flanged collar 38 carried by the blade 35, a collar 39 keyed for slight relative axial motion to the upper end of the arbor 17, and provided with a top flange 39a, these flanges presenting 25 opposed spaced faces, and a ring 40 positioned between these faces and formed of yielding material such as rubber, and preferably a synthetic rubber, since such material is highly resistant to oil. This ring 40 is bonded to both of the collars 38 and 39. Lateral motion of the blade 35 with respect to the arbor 17 then stresses the yielding material 40 in shear, this giving a soft action under comparatively large amplitude of displacement due to the large torsional and lateral vibrations to be expected. This yieldable coupling furnishes the sole driving connection between the arbor 17 and the blade 35. The lower end of the blade 35 which extends below the lower end of the arbor 17 and through the ring 32 is supported 30 in a pair of opposed angular contact bearings 45. The balls of the bearings ride in annular grooves 46 in the perimeter of the blade 35. The two bearings 45 are floating but are yieldably held centered as by a ring of rubber or other cushioning material 47 positioned between and bonded to the outer face of a sleeve 47a enclosing the outer bearing raceways and a sleeve 48 housed within a cap member 50 which is secured to the lower end of the casing 3 as by screws 51. The 35 sleeve 47a may have a flanged cap ring 47b threaded on its lower end, the flange of which supports a pair of Belleville springs 472 which bear beneath the lower outer raceway and load the bearings 45 between the flanges of the sleeves 47a and 48 so that they support the blade rigidly

in axial as well as radial direction. The sleeve 48 may be adjusted by a collar 52 threaded into the interior of the cap 50 and held in position as by a locking threaded collar 53 which may be tightened up against the ring 52. The lower end of the cap 50 is closed over by a flanged end plate 54 having a central perforated boss 55. Through this boss is slidable a short shaft 56 having a head 57 at its lower end. This shaft 56 is keyed against rotation in the boss, as by the key 58, and is normally held partly outwardly projected from the boss 55 as by a coil spring 60. A cross pin 61 which may engage in a transverse slot 62 in an inward extension of the boss 55 acts to prevent undesired removal of the shaft 56. Its upper end is formed with a polygonal extension 63 which may be pressed upwardly into a matingly shaped socket 64 in the lower end of the blade 35 and when in this position locks the blade against rotation for a purpose which will later appear.

The upper portion of the blade 35 is designed to carry a spool 10 provided with the usual large diameter lower flange 71 and the small diameter top flange 72. This spool is provided with spaced sockets 73 in its lower flange within which may ride driving lugs 74 on a spool adapter 75. This spool adapter has a tubular portion 76 internally threaded at its upper end for the reception of a pair of straight threaded plugs 77 and 78. The lower plug 77 may rest upon or abut the upper end of the blade 35 so that turning of this plug 77 adjusts the height of the spool on the blade, and the upper plug 78 acts as a lock nut to clamp the lower plug 77 in adjusted position. Both 35 plugs may have tool-receiving sockets 79 to facilitate turning thereof.

In order that the rotation of the blade 35 may impart rotation to the spool adapter, and with it the spool, means are provided for clamping the upper portion of the blade to the spool adapter. To this end the upper end of the blade 35 is provided with a tapered internally threaded socket 80 within which may be engaged a tapered plug 81 and the upper end of the blade outwardly of the socket is split into segments, three such segments 82 being illustrated in Figure 3. By screwing the tapered plug 80 downwardly, these segments are spread apart and into clamping engagement with the inner wall of the sleeve portion 76 of the spool adapter. The tapered plug 80 may have a polygonal socket 83 in its upper end for the reception of a suitable tool which may be inserted through axial holes 84 and 85 through the straight plugs 77 and 78 and into engagement with the tapered plug 80. In order that this tapered plug may be turned relative to the blade 35, this blade may be held against rotation by engaging with its lower end the extension 63 of the shaft 56 which may be pressed upwardly by the operator for this purpose.

It will be noted that the entire driving connection between the motor rotor and the blade is through the flexible coupling at the upper end of the arbor 17, and the blade has sufficient freedom of motion so that when it and the parts carried thereby are brought up to the desired rotational speed, this organization may normally center itself to rotate about its own center of gravity even though it may not coincide with the axial center of the blade 35. This is important because the yarn pack, including the spool, presents a rotating mass of variable nature. The operation starts with an empty spool and builds up to the final size of the pack. This in itself gives rise to com-

ponent forces effecting the balance, particularly because the load carrying part of the spindle is a rotating cantilever beam. Further component forces arise from the yarn stretch and from the impact when the yarn hits the pack. This impact is heavy, particularly with the heavy yarns now used in tire cord twisting, and is aggravated by increase in speed, which is intended to be particularly high in the mechanism of this invention. There are also unbalanced forces caused by eccentric build-up of the pack, some of which are constant for each spool but differ from spool to spool and are due mainly to variations in looseness of fit between the spool and adapter, and others of which are variable and due to obscure and intricate causes. While the yarn might be expected to be wound evenly and concentric on the spool, actually it is apt to form an elliptical shape with the center of rotation in one of the focal points and it tends to continue to be built up in eccentric form thus increasing the state of unbalance.

In accordance with this invention, therefore, the blade and the parts carried thereby have considerable freedom for self-adjustment for proper rotation, but the cushioning element 47 gives a good damping action, when the blade is exposed to bending or lateral vibration being loaded on one side in tension and on the opposite side in compression, the rubber composition acting softer in tension than in compression. As shown in Figure 2, the clearance between the blade 35 and the arbor 17 is sufficiently large to take care of deflections of the blade under normal conditions, but the arbor acts as a snubber under abnormal conditions which otherwise would impart excessive lateral displacement to the blade. Adjustment of the sleeve 48 may be employed to place a shear load of adjustable amount on the element 47, and where both flange elements of the flexible coupling between the blade and arbor are fixed to their respective carrying parts as is shown in Figure 5, such adjustment of the sleeve 48 acts to adjust the blade axially relative to the arbor, thus to apply a tension or compression load on the flexible element 40 of the coupling. This loading of the flexible element or elements has the effect to tune the spindle and may be employed to advantage in adjusting it to the desired smooth running conditions which may vary, due, for example, to speed changes and changes of load from change of size of the yarn pack, the spool, and other conditions. One or both of the flexible elements 40 and 47 may be electrically conductive. This will have the effect of discharging static electricity from the yarn pack, allowing it to flow to the motor housing 3 which is grounded, as, for example, through the motor windings according to usual practice. If desired, the member 40 may be non-conductive while the member 47 only is conductive, this causing the arbor bearings 18 and 19 to be by-passed during the discharge of such grounded static.

It is also important that no lubricating oil reach the strand which is being twisted and wound upon the spool. To this end the upper end of the casing 3 which is partly closed off by a cover member 86 which carries the upper shaft bearing 18, supports a combined oil trap and guard 87, the upper end of which is inclined over toward the spindle, while beneath the coupling the arbor 17 has an outwardly projecting annular rib 88 which throws off by centrifugal action any oil which may escape upwardly from

the bearing 18 into an annular collecting chamber 89 in the member 87 from which a duct 90 conducts the lubricant into the casing 3 and downwardly through a passage 91 into its lower portion from which it escapes into the cap 53 through a passage 92. A deflector ring 93 having a down-turned margin 94 surrounds the arbor 17 slightly above the lower bearing 19 and its rotation causes foreign particles reaching it to be deflected out into the lower portion of the casing 3.

From the foregoing description of certain embodiments of this invention, it should be evident to those skilled in the art that various changes and modifications might be made without departing from its spirit or scope.

I claim:

1. In combination, a support, a tubular arbor journaled in said support, a blade extending vertically and freely through said arbor, a coupling between said blade and arbor comprising an element carried by and fixed to said blade, an element carried by and fixed to said arbor, said elements having spaced opposed faces, a resilient element between and bonded to said faces, a bearing assembly comprising vibration absorbing and damping means surrounding said bearing assembly supporting the lower end of said blade, and means for adjusting the position of said vibration absorbing and damping means of said bearing assembly relative to said coupling to thereby adjustably load said resilient element.

2. In combination, a support, a tubular arbor journaled in said support, a blade extending vertically and freely through said arbor, a coupling between said blade and arbor comprising an element carried by and fixed to said blade, an element carried by and fixed to said arbor, said elements having spaced opposed faces, a resilient element between and bonded to said faces, a bearing assembly supporting the lower end of said blade, means for adjusting the position of said bearing assembly relative to said coupling to thereby adjustably load said resilient element, a

spool adapter fixed to the blade above the arbor and a spool fixed to the adapter.

3. In combination, a support, a tubular arbor journaled in said support, a blade extending vertically and freely through said arbor, a coupling between said blade and arbor comprising an element carried by and fixed to said blade, an element carried by and fixed to said arbor, said elements having spaced opposed faces, a resilient element between and bonded to said faces, a bearing assembly supporting the lower end of said blade, means for adjusting the position of said bearing assembly relative to said coupling to thereby adjustably load said resilient element, a spool adapter fixed to the blade adjacent the upper end of the blade and a spool fixed to the adapter.
